G. P. MOHR

WATCH MECHANISM

Filed Nov. 28, 1922

Inventor
G. P. Mohr
by Drury & Drayton, Atty's

UNITED STATES PATENT OFFICE.

GEORGE P. MOHR, OF VICTOR, IOWA.

WATCH MECHANISM.

Application filed November 28, 1922. Serial No. 603,759.

To all whom it may concern:

Be it known that I, GEORGE P. MOHR, a citizen of the United States, and a resident of Victor, county of Iowa, and State of Iowa, have invented a certain new and useful Watch Mechanism, of which the following is a specification.

This invention relates to improvements in watch and clock mechanism. Hitherto it has been necessary for a jeweler to entirely disassemble a watch or clock when he wishes to remove the main spring for the purpose of replacement or repairs. This requires a considerable amount of time and is also quite a disadvantage due to the fact that when the various mechanisms which have been delicately adjusted have been torn down, it is hard to replace the same and get it in a perfect working condition, all of which requires a considerable length of time and skill.

It is, therefore, the object of my invention to provide in a watch or clock mechanism improved means for mounting the main spring within the watch casing or frame in such a manner that the main spring may be easily and quickly removed from the casing without removing or demounting the delicately adjusted mechanism of the watch or clock.

More specifically it is the object of my invention to so construct the casing or the mechanism bearing frame of the watch in such a manner that the main spring barrel may be inserted through the edge of the said frame and when inserted, secured in position by placing the pinion through the said barrel and the frame for supporting the same, the pinion being so arranged that when secured in position the various mechanisms of the watch or clock will be placed in operative relation with each other.

My invention consists in the construction, arrangement and combination of the various parts of the device, whereby the objects contemplated are attained, as hereinafter more fully set forth, pointed out in my claims, and illustrated in the accompanying drawings, in which:

Figure 1 is a back view of a segmental portion of one form of a watch showing the manner in which my improved mechanism is applied thereto.

Figure 2 is an enlarged detail sectional view taken on the line 2-2 of Figure 1.

Figure 3 is a back view of a watch show-

ing one of the frame plates removed and part of the winding mechanism to illustrate certain mechanism of the interior construction.

Figure 4 is an edge view of the watch casing showing the opening which is provided for the purpose of receiving the spring barrel, and

Figure 5 is an enlarged detail view of the shaft for supporting the spring barrel and the gear mechanism thereby.

In the drawings I have illustrated the manner in which my device may be applied to one particular form of a watch. It will be obvious that the same general principle may be applied to watch constructions of other makes or to clocks without departing from the spirit of my invention.

The numeral 10 indicates the casing or frame of a watch, the said casing having in its edge an opening 11 which is nearest the point where the spring barrel is mounted and is of such size that the spring barrel may be freely passed through it. The frame 10 is provided with front and back plates 12 and 13, the front plate being provided with a recess 14 which is designed to receive a gear 15. The gear 15 is in mesh with a second gear 16 which is provided with a sleeve 17 extending into the cup portion 18 of the plate 12, the said sleeve 17 being rotatably mounted in the cup portion. The inner edge of the sleeve 17 is provided with a set of beveled teeth 19 designed to co-act with a gear 20.

This gear is mounted on the winding stem 21, as illustrated in Figure 2. The said figure does not show the gear 20 in actual mesh with the gear 19 due to the fact that the front portion of the gear 19 has been cut away on the section line.

The sleeve 17 is secured in position by means of an inner sleeve 22 having an annular flange 23 on its outer end designed to rest in a suitable groove in the wheel 16. The sleeve 22 is secured in position by means of a set screw 24. By this arrangement it will be seen that rotary movement may be imparted to the gear 15 through the stem 21 and the co-acting gear members 20 and 19 through the sleeve 17 and the gear 16.

Between the plates 12 and 13 and opposite the gear wheel 15 is a spring drum 25, this drum being formed with a cylindrical portion and an end portion 26, the opposite end

of the cylindrical portion being provided with an end member 27 which is detachably mounted therein.

Pivotedly mounted in the center of the end members 26 and 27 is a sleeve 28 having an enlarged portion 29 to which one end of the main spring 30 is secured, the opposite end of the spring being secured to the cylindrical portion 25. The sleeve 28 is of a length equal to the length of the cylindrical member 25 and so arranged that its end is even with the outer face of the sleeve 28, the said sleeve being rotatably mounted in said ends. The said sleeve is provided with a centrally located square opening 31 designed to receive a square shaft 32, the back end of the shaft 32 being provided with a round or pinion portion 33 designed to be mounted in suitable bearings in the plate 13. The opposite end of the shaft 32 is provided with a round bearing 34 which is slightly larger in diameter than the shaft 32 and designed to be rotatably mounted in bearings in the plate 12. The front end of the portion 32 is provided with a square portion 35 designed to enter a square opening in the gear wheel 15, the said gear being secured in position on the shaft by means of a set screw 36, the head of which is even with the inner face of the gear 15.

By this arrangement it will be seen that by removing the set screw 36 and the gear 15 that the shaft 32 may be pulled out of the sleeve 28 through the back side of the case. When the shaft 32 has been removed the spring barrel may then be moved laterally through the opening 11 of the case, after which the spring may be removed by simply removing the head 27. After the necessary repairs have been made the barrel may then again be replaced until the opening 31 is in alignment with the openings of the plates 12 and 13 after which the shaft 32 may be placed into position, the gear 15 replaced and secured in position by the screw 36.

To prevent the gear 19 from moving out of the recess 14 and carrying with it the shaft 32, I have placed a bar 37 across the back face of the gear 15 and over the head of the screw 36, having one end of the bar 37 screwed to the flange 23 of the sleeve 22 by means of screws 38. The opposite end of the bar 37 is secured to the frame of the casting by means of a screw 39.

By the construction of the sleeve 22 being pivotally mounted in the sleeve 17 and upon the screw 24 it will be seen that it is not necessary to remove the screws 38 when it is desired to remove the shaft 32, the said shaft 32 being removed by simply removing the screw 39 and swinging the bar 37 to position illustrated in dotted lines in Figure 1. In order to do this it might be nec-

essary to slightly loosen the screw 24 which is easily accomplished by placing a screw driver through the opening 40 of the bar 37, after which the gear 15 may be removed as before described.

It is obvious that various ways may be provided for retaining the shaft 32 against coming out of position in the sleeve 28 without departing from the spirit of this invention. The cylindrical portion 25 of the barrel is provided with a gear 41 which is designed to mesh with the pinion wheel 42 of the shaft 43. This shaft 43 is provided with a second gear 44 which operates the various mechanisms of the watch. The gear 15 is held against movement in one direction by means of a pawl. When the watch is being wound through the stem 21, as before described, the gear 15 will rotate the sleeve 28 and the enlarged portion 29 causing the spring 30 to be wound up. The barrel 25 will then be rotated in the opposite direction, driving the gear 41 and its co-acting gears as before described.

By this arrangement it will be seen that I have provided an improvement in the construction of watches which will enable the jeweler to easily and quickly remove the spring barrel without interfering with the delicately adjusted mechanism and which may be accomplished in a few minutes' time thereby providing a considerable saving in the jeweler's time and expense in having the watch repaired.

I claim as my invention:

1. A watch comprising a frame, front and back plates spaced apart and parallel to each other, a shaft rotatively mounted in said plates, a spring barrel mounted to rotate about the axial center of said shaft, a watch mechanism, means for driving the watch mechanism by the rotation of said barrel, a spring within said barrel having one end connected thereto, means for detachably connecting said spring in operative relation with said shaft, a winding mechanism detachably secured to said shaft, said shaft being capable of longitudinal movement to disconnect it from the mechanism operatively connected therewith, the said shaft also being adapted to support the spring barrel between said plates, and further so arranged that the barrel may be slidably removed from between the said plates when the shaft has been moved.

2. A watch mechanism comprising a frame having spaced front and back plates, said frame being provided with an opening, a spring barrel slidably mounted between said plates and inserted through said opening, a shaft pivotally mounted in said plates and extending centrally through said barrel, a spring within said barrel having one end connected thereto, means for detachably securing the opposite end of said spring in

operative relation with said shaft by sliding the shaft longitudinally through the barrel, and means detachably connected with said shaft for winding the same.

5 3. A watch mechanism comprising a frame having front and back plate members spaced apart, said frame being provided with an opening, a spring barrel being designed to be moved into position through 10 said opening and between said plates, a sleeve rotatably mounted in said barrel, a spring within said barrel having one end connected to said barrel and the opposite end connected to said sleeve, said sleeve be-

ing provided with a central longitudinal 15 opening, a shaft pivotally mounted through one of said end plates designed to rest in said longitudinal opening and to be pivotally connected in the opposite end plate, a gear detachably secured to the outer end of 20 said shaft and means for detachably securing said shaft within said sleeve, said shaft being slidably and non-rotatably mounted in said sleeve and a gear mechanism driven from said drum.

Des Moines, Iowa, November 17, 1922.

GEORGE P. MOHR.
